 doing business as Nepo Manufacturing Co., a
 copartnership

Application October 9, 1952, Serial No. 313,879

1 Claim. (Cl. 248—289)

1

This invention relates to a bracket for mounting overhanging and outwardly extending floodlights and the like.

Frequently, in outdoor installations the problem of maintenance of the floodlights, such as cleaning the reflector or replacing a burned out bulb, becomes a difficult, awkward, and sometimes a hazardous task. This is particularly true where the light fixture, which includes the reflector and bulb, is disposed in a fixed position relatively high above the ground and spaced a considerable distance outwardly from the supporting wall.

Thus it is one of the objects of this invention to provide a bracket which eliminates the above noted maintenance problems.

It is a further object of this invention to provide a bracket which is simple and compact in construction, yet provides adequate support for the floodlight, is easy to install, and is inexpensive to produce.

Further and additional objects will appear from the description, accompanying drawings and appended claims.

In accordance with one embodiment of this invention, a bracket is provided comprising a base, an apertured hollow support mounted on said base and projecting transversely therefrom, and an apertured hollow connecting piece swivelly mounted within said support and in communication with the interior thereof. Mounted on the support and engaging the connecting piece is adjustable means which, when in one position of adjustment, effects locking of said connecting piece with respect to said support.

For a more complete understanding of this invention reference should be made to the drawings wherein:

Figure 1 is a fragmentary perspective view of the improved bracket shown in combination with a floodlight and a supporting wall;

Fig. 2 is a side elevational view of the bracket;

Fig. 3 is a right end view of the bracket shown in Fig. 2;

Fig. 4 is a sectional view of the bracket taken along line 4—4 of Fig. 2;

Fig. 5 is a sectional view of the bracket taken along line 5—5 of Fig. 2;

Fig. 6 is a back view of the bracket shown in Fig. 2;

Fig. 7 is similar to Fig. 2, but showing portions of the bracket broken away; and

Fig. 8 is a sectional view of the bracket taken along line 8—8 of Fig. 7.

Referring now to the drawings and more par-

ticularly to Fig. 1, the improved bracket 10 is shown for mounting an outdoor type floodlight 11 to a wall 12, the latter in this instance being of masonry construction. The floodlight 11 comprises a lighting fixture 13, which, among other things, includes a reflector and bulb, not shown. The lighting fixture 13 is connected by means of a curved pipe or conduit 14 to the bracket 10. Disposed within the conduit 14 are electrical leads or wiring 15 for the lighting fixture. If additional support for the floodlight 11 is desired, a brace 16 may be employed which, as shown in Fig. 1, is connected at one end to the curved conduit 14 and at the other end to the wall 12.

The improved bracket 10, seen more clearly in Figs. 2 and 7, comprises, in this instance, a casting 17 which includes a substantially flat base 18, the latter being secured by means of a plurality of attaching bolts 20 to the wall 12. The casting 17 includes also a support 21 which projects outwardly at substantially a right angle from the base 18. The support 21, in turn, comprises an apertured hollow first portion 22, which is integrally connected to base 18 at one end. A second apertured hollow support portion 23 is integrally connected to the outer end of the first portion 22 and is disposed at substantially a right angle with respect thereto. The first support portion 22 is provided with an internally threaded opening 24, adjacent the base 18, and is adapted to threadably receive a conduit 25 in which electrical leads or wiring 26 are carried from the source of electrical power, not shown, to the bracket. First support portion 22 is provided with an enlarged second opening 27 which is adapted to be closed off by a demountable cover piece 28. The aperture 27 enables the installer to have access to the interior of the support 17 in order to connect together at points 30, the ends of leads 15 and 26, see Fig. 7. A threaded third opening 29 is formed in support portion 22 and is disposed directly opposite aperture 27 to enable the conduit 25 to be introduced at this point instead of opening 24, if so desired. The threaded opening 29 may be closed off by a plug 29a. The hollow interior of first support portion 22 communicates with the hollow interior of second support portion 23 through passageway 31, see Fig. 7.

Swivelly mounted within second support portion 23 is an elongated connecting piece 32 which is threaded at both ends. The connecting piece 32 is in the form of a pipe nipple and has an elongated slot 33 formed therein which is adapted

3

to communicate with an annular recess 34 formed in the interior of the second support portion 22, see Fig. 7. The annular recess communicates with the passageway 31 and is of sufficient size so as to enable the electrical leads 15 to be readily positioned therein without binding, when the connecting piece 32 is turned relative to support portion 23. The lower end of connecting piece 32, in this instance, is closed off by a threaded cap 35 and gasket 36. Threadably mounted on the opposite end of the connecting piece 32 is an internally threaded pipe connector 37 which interconnects the bracket 10 and the lower end of conduit 14.

Means are provided on the second support portion 23 for locking the connecting piece 32 in a position of swivel adjustment with respect to the bracket. The means, in this instance, is in the form of a pair of spaced locking screws 38, which are threadably seated within suitable openings formed in support portion 23. The screws 38, when drawn up tight, have the inner ends thereof biting into the periphery of the connecting piece so as to hold the latter in a fixed position with respect to the bracket.

When it is desired to service the lighting fixture 13, such as cleaning the reflector or replacing a burned out bulb, all that is required of the workmen is to loosen the locking screws 38 and bolt 40, the latter holding the inner end of brace 16 securely to a brace bracket 41 which, in turn, is mounted on wall 12; and then swing the floodlight in either direction through an arc of approximately 90° so that the lighting fixture 13 is adjacent the wall 12. When the floodlight is swung to this position, the workmen may readily service the lighting fixture with comparative ease. Once the servicing has been completed the floodlight is once again swung away from the wall 12 to a position as shown in Fig. 1, whereupon bolt 40 and locking screws 38 are drawn up tight.

While the bracket 10 has heretofore been discussed and shown to be used in combination with a vertical wall, it is to be understood, of course, that such a bracket may be used when mounting floodlights on a horizontally disposed roof or any other surface not vertically disposed. Furthermore the conduit 14 may vary in size and shape depending on the particular installation.

Thus, it will be seen that an improved bracket has been provided which eliminates the awkwardness and hazards which heretofore had been associated with servicing floodlights wherein the lighting fixture thereof was disposed in a fixed position away from the supporting wall and at a considerable distance above the ground or floor. Furthermore, the improved bracket is of simple compact construction, yet provides adequate support for the floodlight, is easy to install, and is inexpensive to produce.

4

While a particular embodiment of this invention is shown above, it will be understood, of course, that the invention is not to be limited thereto, since many modifications may be made, and it is contemplated, therefore, by the appended claim, to cover any such modifications as fall within the true spirit and scope of this invention.

I claim:

A bracket comprising a support for attachment to a stationary member, said support including an apertured hollow first section mounted on such a stationary member and extending transversely therefrom and being provided with a passageway disposed adjacent the portion of said first section engaging such stationary member and communicating with the interior of said first support section, and an apertured hollow second section integral with said first section and disposed substantially at right angles with respect thereto and spaced from the stationary member on which said first section is mounted, said second section including a pair of spaced aligned bushing portions, an elongated hollow apertured cylindrical connecting element disposed within said second support section, and supported for swivel movement by said bushing portions, said connecting element having a peripheral portion thereof disposed intermediate said bushing portions and with the interior of said second section spaced therefrom to form an annular passageway therebetween communicating with the interior of said first section, said peripheral portion of said connecting element being provided with an elongated aperture communicating with the interior of said second section and said annular passageway, the center of curvature of said aperture being coincident to the swivel axis of said element, said elongated aperture having a portion thereof in rectilinear alignment with the interior of said first section upon relative movement of said element through a sector of at least 90°, and adjustable means mounted on said support and contacting said connecting element for locking the latter in a fixed position of swivel adjustment.

NATHAN E. PASSMAN.
